CLAIM

The ornamental design for a tab, as shown and described.

DESCRIPTION

FIG. 1 is a top perspective view of tab;
FIG. 2 is an enlarged top perspective view thereof;
FIG. 3 is an enlarged top perspective view thereof, showing the tab in an alternative configuration;
FIG. 4 is another enlarged top perspective view thereof, showing the tab in the same configuration as FIG. 1;
FIG. 5 is a cross-sectional view taken in the direction of line 5-5 shown in FIG. 2; and,
FIG. 6 is a cross-sectional view taken in the direction of line 6-6 shown in FIG. 3.

The broken lines show environment for my design and form no part of the claimed design.

1 Claim, 5 Drawing Sheets
